US0D1058589S

(12) **United States Design Patent** (10) Patent No.: **US D1,058,589 S**
(45) Date of Patent: ** *Jan. 21, 2025

(54) **DISPLAY SCREEN WITH GRAPHICAL USER INTERFACE**

- (71) Applicant: **WAPP TECH Corp.**, Red Deer (CA)
(72) Inventor: **Donavan Paul Poulin**, Kelowna (CA)
(73) Assignee: **WAPP TECH Corp.**, Red Deer (CA)
(*) Notice: This patent is subject to a terminal disclaimer.
(**) Term: **15 Years**
(21) Appl. No.: **29/939,378**
(22) Filed: **Apr. 26, 2024**

Related U.S. Application Data

- (63) Continuation of application No. 17/657,213, filed on Mar. 30, 2022, now Pat. No. 11,971,812, which is a continuation of application No. 16/510,928, filed on Jul. 14, 2019, now Pat. No. 11,327,875, which is a continuation of application No. 15/979,330, filed on May 14, 2018, now Pat. No. 10,353,811, which is a continuation of application No. 14/581,475, filed on Dec. 23, 2014, now Pat. No. 9,971,678, which is a continuation of application No. 13/673,692, filed on Nov. 9, 2012, now Pat. No. 8,924,192, which is a continuation of application No. 12/759,543, filed on Apr. 13, 2010, now Pat. No. 8,332,203, which is a continuation of application No. 11/449,958, filed on Jun. 9, 2006, now Pat. No. 7,813,910.

CLAIM

The ornamental design for a display screen with graphical user interface as shown and described.

DESCRIPTION

The FIGURE is a front view of a display screen with graphical user interface showing my new design. The dashed broken lines illustrate portions of the graphical user interface and form no part of the claimed design. The dot-dash broken lines illustrate the perimeter of a display screen and form no part of the claimed design.
